ATTORNEY.

UNITED STATES PATENT OFFICE.

PERCY J. CALLOWHILL, OF NORTH ATTLEBORO, MASSACHUSETTS, AS-
SIGNOR TO BRISTOL MANUFACTURING COMPANY, A CORPORATION OF
RHODE ISLAND.

DESIGN FOR A BACK FOR MIRRORS, BRUSHES, OR SIMILAR ARTICLES.

No. 38,175.

Specification for Design.

Patented Aug. 21, 1906.

Application filed June 26, 1906. Serial No. 323,537. Term of patent 3½ years.

To all whom it may concern:

Be it known that I, PERCY J. CALLOWHILL, a subject of the King of Great Britain, residing at North Attleboro, in the county of Bristol and State of Massachusetts, have invented a certain new, original, and ornamental Design for a Back for Mirrors, Brushes, or Similar Articles, of which the following is a specification, reference being had therein to the accompanying drawing.

The figure is a plan view of a back for a mirror, brush, or similar article embodying my new design.

I claim—

The ornamental design for a back for mirrors, brushes, or similar articles, as shown.

PERCY J. CALLOWHILL.
